UNITED STATES PATENT OFFICE.

MARY L. SCHULTZE, OF HOBOKEN, NEW JERSEY, ASSIGNOR TO JOHN MEHL & COMPANY, OF JERSEY CITY, NEW JERSEY, A CORPORATION OF NEW JERSEY.

DESIGN FOR A BILL-BOOK.

SPECIFICATION forming part of Design No. 35,495, dated December 31, 1901.

Application filed May 18, 1901. Serial No. 60,951. Term of patent 7 years.

To all whom it may concern:

Be it known that I, MARY L. SCHULTZE, a citizen of the United States, and a resident of Hoboken, in the county of Hudson and State 5 of New Jersey, have invented and produced a new and useful original Design for a Bill-Book, of which the following is a specification.

The leading feature of my design consists of a bill-book presenting when unfolded and 10 looked at from one side an oblong portion with tapered end and a smaller laterally-extending portion offset therefrom intermediate of the ends of the said oblong portion and when viewed from the opposite side presents 15 an oblong portion with tapered end and a laterally-extended flap, the face of the flap being provided with a marginal border surrounding an opening into a pocket, the mouth of the pocket being located at the inner ends of the 20 flap.

In the accompanying drawings, Figure 1 represents the bill-book opened out as it ap-

pears when looked at from one side, and Fig. 2 is a similar view showing the appearance of the book when looked at from the opposite 25 side.

a represents the blank portion with the tapered end *b*.

c represents the laterally-extending flap, and *d* the marginal border surrounding the 30 pocket-opening *e* in the face of the flap. The mouth of the pocket is denoted by *f*.

What I claim is—

The design for a bill-book, substantially as herein shown and described. 35

In testimony that I claim the foregoing as my invention I have signed my name, in presence of two witnesses, this 16th day of May, A. D. 1901.

MARY L. SCHULTZE.
